ATTORNEY

UNITED STATES PATENT OFFICE.

RUDOLPH ROLLINGER, OF CHICAGO, ILLINOIS.

OUTSIDE WALL.

984,517.

Specification of Letters Patent. Patented Feb. 14, 1911.

Application filed February 28, 1910. Serial No. 546,429.

To all whom it may concern:

Be it known that I, RUDOLPH ROLLINGER, a subject of the King of Hungary, and a resident of Chicago, in the county of Cook and State of Illinois, have invented certain new and useful Improvements in Outside Walls, of which the following, when taken in connection with the drawing accompanying and forming a part hereof, is a full and 10 complete description, sufficient to enable those skilled in the art to which it pertains to make, use, and understand the same.

This invention relates to outside walls of buildings and other constructions; and the 15 object of the invention is to obtain an outside wall constructed of concrete or cement and tiles in an economical manner, which will be durable, of good or finished appearance, and of sufficient strength to withstand the strains to which it is subjected.

Outside walls of the kind embodying this invention are used principally for the front, sides and back of detached buildings, and for the front and back of buildings provided 20 with party walls.

In the drawing referred to Figure 1 is a horizontal sectional view of a portion of a wall embodying this invention. Fig. 2 is a vertical sectional view of a portion of 25 a wall embodying the invention. Fig. 3 is a front elevation of a portion of a wall embodying the invention. Fig. 4 is a perspective of a tile forming an element in the wall embodying the invention; and 30 Fig. 5 is a perspective of a tie or brace forming an element of the wall.

A reference letter applied to designate a given part is used to indicate said part throughout the several figures of the drawing 40 wherever the same appears.

A is a tile, provided on the upper and lower edges thereof with the recesses a. B is a tie or brace, made of metal and provided at one end with the upturned portions b, b, and the downturned portions b', and at the other end provided with aperture b''.

The upturned ends b, b, fit into the recesses a, on the lower edge of a given layer 50 of tile and the end b' fit into the recess a on the upper edge of the next lower layer of tile. It will be observed, when the tiles are laid in the usual manner, so that the breaks in one row of tile come midway of the 55 breaks in the next adjacent row, that the upturned ends b, b, come in the end ones of

the recesses on a given tile, and that the downturned end b' comes in a recess midway of the tile. Each tile is therefore, held in place by not less than three ties or braces 60 B; that is, each tile will have a tie at both of its lower corners, and also a tie midway of its ends on its upper edges. Additional ties may be employed, if desired.

C, C, are wooden strips; and D, D, are 65 planks or boards.

The ties are attached to strips C by nails or bolts E, E, and the planks or boards are attached to the strips by nails or bolts E'.

After the several parts hereinbefore referred to are attached together in the manner described the concrete F is flowed or run into place between the tiles A and the boards or planks D, D, and allowed to dry, or harden. After the cement F is hardened 75 sufficiently the boards or planks D are removed, leaving the strips C embedded in the cement or concrete of the wall.

The tiles A are held firmly in place by the cohesion of the cement or concrete and 80 also by the ties B.

The space between the tiles A, of one row and the tiles of the next adjacent row may be filled with mortar, after the cement or 85 concrete F is hardened.

The strips C, embedded as described, are used to attach lathing or other material to the inside of the wall, after said wall is completed, but the attaching of lathing or other material to said strips is not a material 90 part of the invention.

Having thus described my invention, what I claim as new and desire to secure by Letters Patent is,

1. As a new article of manufacture, an 95 outer wall consisting of a cement body, strips in said cement body, one side of said strips exposed on one of the vertical faces of said cement body, and said strips adapted to form bases for the attachment of articles to both faces of said cement body, tiles on the opposite vertical face of the cement body from the strips, said tiles provided with recesses on the edges thereof, and ties, said ties extending through the cement 105 body and provided with projections at one end arranged to fit in the recesses of the tiles and provided with means at the other end to attach said ties to the strips.

2. The combination of a cement body, tiles 110 arranged in a plurality of rows on one of the vertical faces of said cement body, said

tiles respectively provided with recesses on the upper and lower edges thereof, metal ties respectively provided with an aperture at one end and with projections at the other end, said projections positioned to engage with the recesses in the tiles, strips on the opposite face of the cement body from the tiles, means to attach the strips and the ties together, said strips surrounded on three sides by said cement body and the remaining

side of said strips in substantially the same plane as the opposite vertical face of said cement body from the tiles, and said strips adapted to form bases for the attachment of articles to both of the vertical faces of said cement body.

RUDOLPH ROLLINGER.

In the presence of—

ADOLPH D. WEINER,

CHARLES TURNER BROWN
